UNITED STATES PATENT OFFICE.

NEAL LARKIN ANDERSON, OF WINSTON-SALEM, NORTH CAROLINA.

TYPE-WRITER CARRIAGE-RETURN MECHANISM.

1,226,296.

Specification of Letters Patent.

Patented May 15, 1917.

Application filed March 29, 1916. Serial No. 87,402.

To all whom it may concern:

Be it known that I, NEAL L. ANDERSON, a citizen of the United States, residing at Winston-Salem, county of Forsyth and State of North Carolina, have invented certain new and useful Improvements in Type-Writer Carriage-Return Mechanism; and I do hereby declare the following to be a full, clear, and exact description of the invention, such as will enable others skilled in the art to which it appertains to make and use the same.

This invention is directed to the provision of an improved form of return mechanism for a typewriter carriage including a motor suitably connected to the typewriter carriage and adapted to effect the return of the carriage automatically on the depression of a suitable key.

20 The primary feature of the invention involves the provision of means whereby the typewriter carriage is relieved of the drag of the return mechanism connected therewith while the carriage is being moved in the ordinary manner to effect letter spacing, as for instance, by the spring usually provided for moving the carriage in one direction under the control of the escapement mechanism. It has heretofore been proposed to provide an electric motor for returning a typewriter carriage, the armature of this motor being connected to the carriage either directly or through a suitable flexible connection. In such constructions, the movement of the carriage during the writing of a line of print has been accompanied by rotation of the armature of the motor of the return mechanism and the spring provided for effecting the letter spacing movements of the carriage has had imposed upon it the additional work of so rotating the armature of the motor. Such increase in load upon the spring results in retarding the movements of the typewriter carriage and the speed at which the machine may be operated is greatly reduced. In accordance with the present invention the motor employed for returning the typewriter carriage imposes no additional load upon the spring of the typewriter carriage. Instead, the motor is operated automatically as the typewriter carriage is moved in writing a line of print so that the armature of the motor turns in correspondence with the movements of the typewriter car-

riage; the motor thus maintains its operative connection to the carriage so that it is in readiness at all times to effect a return movement of the carriage but the spring for actuating the typewriter carriage is wholly relieved of the work of rotating the motor armature as the carriage moves to effect letter spacing.

The feature of the invention above referred to whereby the spring for actuating the typewriter carriage is relieved of the drag of the motor is preferably combined with a tension regulator of the character disclosed in Patent No. 953,938, heretofore granted to me, though it may be used, if desired, in a type of return mechanism wherein the return motor is connected directly to the carriage, as by means of a rack on the carriage meshing with a gear on the motor shaft. The mechanism disclosed in the patent above referred to involves the provision of a flexible connection from the carriage of the typewriter to the armature of the motor for effecting the return of the carriage and a controlling member is combined with this flexible connection in such a way as to cause actuation of the motor whenever the flexible connection becomes slack so as to take up the slack in that connection and restore it to its initial condition. For instance, it would frequently happen that the operator of a typewriter equipped with a return mechanism would want to return the carriage by hand through a short distance and such manual return of the carriage unaccompanied by actuation of the return motor would result in slackening the flexible connection. Under such conditions the automatic take-up above referred to would cause operation of the motor so as to wind up the flexible connection an amount sufficient to restore it to its original taut condition. In accordance with the present invention, I arrange the controller of the take-up mechanism so that it operates to cause rotation of the motor both for taking up slack in the flexible connection and also for feeding out the flexible connection in correspondence with the letter spacing movements of the typewriter carriage. Preferably, an electric motor is employed for effecting the return of the carriage and a flexible connection is fastened at one end to the carriage and at the other to a pulley on a shaft driven by the motor armature. A

controller is provided bearing against this flexible connection and arranged to control the circuits of the motor in such a way that it may close the motor circuits in one direction or in the other. The arm of the controller bears with spring pressure upon the flexible connection and if that connection becomes slack, the controller arm is moved by its spring so as to close circuit through 5 the motor in such a direction as to effect operation of the motor in the direction appropriate for taking up the slack. On the other hand, if the normal slack of the flexible connection is taken up, as it would be as a result 10 of letter spacing movements of the typewriter carriage, then the arm of the controller would be moved to a position for closing the circuits of the motor in the opposite direction and thus cause operation 15 of the motor in a direction to unwind the flexible connection from the pulley on the motor-driven shaft so as to feed out the flexible connection and thus restore it to its original condition. The operation of the 20 mechanism in this respect is such that the motor is always maintained in proper operative condition with respect to the typewriter carriage. The operation of the motor to return the carriage is not accompanied 25 by racking of the parts such as would result if the first portion of the movement of the motor were a movement incident to taking up a substantial amount of slack in the flexible connection and the 30 spring for actuating the typewriter carriage is wholly relieved of the load which would be imposed upon it if it were necessary for the movement of the carriage to effect directly the rotation of the motor armature. 35 Another feature of the invention involves the provision of a return mechanism of such a construction as will permit of the use of a return motor of very small size. To this end the motor is connected to the typewriter carriage through speed reducing gearing. This is made possible by reason of the provision of the automatic mechanism for actuating the motor to unwind the flexible connection in correspondence with the letter 40 spacing movements of the typewriter carriage. In prior types of carriage return mechanisms, the use of such speed-changing gearing in the connections from the carriage to the motor shaft has been practically impossible because of the fact that the movement of the carriage itself was depended upon to effect the rotation of the motor armature and the drag thus imposed 45 on the motor armature would be substantially increased if such speed-changing gearing were employed. In accordance with the present invention wherein the motor is operated automatically to feed out the flexible connection as the letter spacing 50 movements of the carriage occur, the motor

may be connected through speed-changing gearing to the shaft on which is mounted the pulley for the flexible connection and because of this a motor of much smaller size may be employed and the current consumed 55 therein is greatly reduced.

Another feature of the invention involves the provision of means for facilitating the assemblage of the flexible connection or the insertion of a new flexible connection when an old one becomes broken. This feature of the invention also involves protecting the mechanism against injury due to operation of the motor following a break in the flexible connection, in which case the motor would not be brought to rest by the means provided for opening the motor circuit under normal conditions.

The invention also involves the provision of certain improvements in the mechanism 60 employed for controlling the speed of the return movement of the carriage. In Letters Patent No. 1,187,124 heretofore granted to me, a construction is shown wherein the circuit of the motor of the carriage return 65 mechanism is automatically controlled so as to insert resistance in the motor circuit toward the end of a return movement of the carriage, the amount of this resistance being regulated in accordance with the extent of 70 the advance movement of the carriage. Thus, when the carriage is returned the full length of a line of print, the maximum resistance would be cut into the motor circuit near the end of the return movement of the 75 carriage so that this final operation of the return movement would be effected under the momentum gained by the carriage in the preceding portion of the return movement. When the carriage is returned through a short 80 distance only, it would not gain so much momentum and therefore if the same amount of resistance were cut into the motor circuit at the same point in the return movement, it might frequently happen that the 85 return movement would not be completely effected. The amount of the resistance cut into the motor circuit is therefore automatically regulated in such a manner that when the carriage is returned through a short 90 distance only, a less amount of resistance would be cut into the motor circuit and the torque of the motor would therefore be reduced to a limited extent only; as a result, if the momentum of the carriage were insufficient to effect a complete return of the carriage, the operation of the motor would be available to complete the return movement. The present invention involves the provision 95 of an improved construction of the parts whereby this automatic regulation of the resistance of the motor circuit under the varying conditions of return movements is attained. It also involves the provision of a 100 convenient and readily operated mechanism 105

for adjusting the point in the return movements where the resistance proportioned to the extent of the advance movement is cut into the motor circuit.

5 These and other features of the invention will be better understood by reference to the following description taken in connection with the accompanying drawings which show the preferred embodiment of the invention.

In these drawings, Figure 1 is a front view of a typewriter having the return mechanism applied thereto; Fig. 2 is a top view of a portion of the typewriter shown in Fig. 1; Fig. 3 is a central longitudinal section of the return mechanism, certain of the parts being shown in elevation; Fig. 4 is a top view of the mechanism shown in Fig. 3, the casing of the return mechanism being in section; Fig. 5 is a view of the key lever and the contacts controlled thereby in section on line 5—5 of Fig. 8; Fig. 6 is a transverse section of the parts shown in Fig. 3 on line 6—6 of Fig. 3; Fig. 7 is a transverse section through the rheostat; Fig. 8 is a transverse section of the return mechanism on line 8—8 of Fig. 3; Fig. 9 is a detail view in horizontal section on line 9—9 of Fig. 8; Fig. 10 is a view in vertical section on line 10—10 of Fig. 8; Fig. 11 is an enlarged view of the top of the rheostat; and Figs. 12, 13 and 14 are diagrams of the circuits.

Referring to these drawings, 16 indicates a typewriter having the usual reciprocating paper carriage 17 provided with a rotary platen 18 upon which a sheet of paper is supported. The carriage 17 is moved transversely of the machine by a spring under the control of an escapement mechanism to effect letter spacing, and the platen 18 is rotated step by step to effect line spacing. To the right of the carriage is the usual pivoted and spring retracted line-spacing lever 19 provided with a handle 20 which is grasped by the operator in order to return the carriage and at the same time rotate the platen to effect line spacing. The automatic return of the carriage is effected by a motor located within the casing 21. This motor actuates a shaft 22 on which is mounted a pulley 23 and one end of a flexible connection 24 is wound upon and secured to this pulley 23. The flexible connection 24 extends over a pulley 25 mounted upon the frame of the typewriter and its end is connected to the carriage 17 of the typewriter. Preferably this end of the connection 24 is secured to a bar 26 which is mounted upon the carriage 17 and adapted to move relatively thereto in suitable guides 27. This bar 26 is pivotally connected to one end of a crank 28 which is secured to the handle of the line-spacing lever 20 so that when the motor winds up the flexible connection 24 it not only returns the carriage but also oper-

ates the parts 19, 20 and 28 so as to effect line spacing.

The arm 29 of a controller for the motor for effecting the return of the carriage carries a roller at its end which roller bears upon the flexible connection 24. The arm 29 is pivotally mounted and is actuated by a spring so as to bear upon the flexible connection 24 with a light pressure sufficient to flex the connection 24 slightly, as is indicated in Fig. 1. If the operator returns the carriage more or less by hand, the flexible connection 24 is slackened and arm 29 is immediately turned by its spring and in so turning closes the circuits of the motor in the casing 21 so as to cause operation of the motor to take up the slack in the connection 24. On the other hand, if the typewriter is operated, the carriage 17 will be moved by its spring step by step to effect letter spacing and such movement of the carriage will tend to draw the flexible connection 24 more taut, resulting in movement of the arm 29 of the controller in the opposite direction against the tension of its spring and thus closing the circuits of the motor in a reverse direction; as a consequence of which the motor will operate to feed out the flexible connection 24 until the normal slack in the connection has been reestablished.

Referring now to Figs. 3 to 11, the motor for returning the carriage is shown at 30. On its shaft is a pinion 31 meshing with a gear 32 on the driven shaft 22 on which the pulley 23 is secured. The shaft 22 carries a worm 33 which meshes with a worm wheel 34 on a vertically disposed shaft 35. This shaft is journaled at its lower end in a bearing formed in the base plate 36 of a rheostat. This rheostat includes coils of resistance wire 37 wound upon a spool located below the plate 36 and a plurality of contacts 38 which are connected to the resistance wire 37 at various points thereon, as will be understood by reference to the diagrams of circuits shown in Figs. 12, 13 and 14. A disk 39 is mounted loosely upon the shaft 35 and this disk carries an arm 40 on the end of which is a contact adapted to move over the series of contacts 38 as the disk 39 is turned on shaft 35. As stated above, the disk 39 is loose on the shaft and it is turned in one direction by an arm 41 projecting outwardly and downwardly from a collar 42, which is secured to the shaft 35 directly below the worm wheel 34. When shaft 35 is rotated carrying with it the arm 41, this arm engages a stud 43 rising from the disk 39 and turns the disk with it so as to carry the arm 41 around over the resistance contacts 38. Between the disk 39 and sleeve 42 is a coiled spring 44 which is placed under tension when shaft 35 is turned in a counterclockwise direction, as seen in Fig. 4, while the disk 39 is held against ro-

tation. This spring, when so placed under tension, is employed for retracting the disk 39 and arm 40 to their initial positions when the disk is released.

6 The disk 39 and arm 40 are adapted to be held in positions to which they are moved by a lever 45 pivoted upon the plate 36 and provided with a tooth which is adapted to coact with ratchet teeth formed in the edge 10 of a portion of the disk 39. This lever 45 is adapted to be turned by a spring 46 in a direction to cause its tooth to engage the ratchet, but normally the lever is held out of coaction with the ratchet by a cam 47 on 15 the key lever 48 of the return mechanism, as is shown in Fig. 5. This key lever is pivotally mounted upon the base of the return mechanism and its free end projects therefrom to a position convenient for the 20 operator, as is shown in Fig. 1. When the key lever is in its normal elevated position, the cam 47 holds the spring-actuated lever 45 retracted out of coaction with the teeth of the ratchet on disk 39. But when the key 25 lever is depressed, the cam 47 releases lever 45 and spring 46 actuates that lever so as to cause its tooth to engage the ratchet on disk 39 and thus hold the disk 39 and arm 40 in the positions to which they have been 30 moved until the key 48 is released and is returned to its initial position by its spring. When this occurs, the cam 47 moves lever 45 to cause it to release the ratchet and disk 39 and arm 40 are returned to their initial 35 positions in contact with the first one of the studs 38 by the spring 44.

Adjacent to the disk 39 is a lever 49 which is pivotally mounted upon the base plate 36 of the rheostat. A spring 50 is connected to 40 this lever and to a stud on the base plate, the spring being adapted to turn lever 49 in a clockwise direction. The end of lever 49 is adapted to make contact with a pin 51 mounted upon the end of a lever 52 which is also pivotally mounted upon the plate 36 of the rheostat. The lever 52 is normally held in the position in which it is shown in Figs. 4 and 11 by a leaf spring 53 which is secured to the edge of the plate 36 and 50 which bears against a pin 54 depending from the lever 52. The lever 52 is extended beyond its pivot and the extension 55 is adapted to be engaged by a cam 56 mounted upon the end of a shaft 57. This shaft is 55 adapted to rock in a bearing provided for it in the casing of the return mechanism and exterior to the casing it is provided with a handle 58 whereby the cam 56 may be adjusted to any desired angular position. 60 When cam 56 is so turned, it turns the lever 52 about its pivot and through the pin 51 it correspondingly moves the lever 49. The lever 49 is adapted to be moved against the tension of spring 50 so as to break the contact between the end of the lever and the pin

51 by means of the arm 41 projecting from the sleeve 42 on the shaft 35 of the rheostat, as will be hereinafter more fully described in connection with the circuits.

Summarizing the operation of the parts 70 just described, the movement of the carriage to effect letter spacing throughout the printing of a line causes rotation of the shaft 22 to feed out the flexible connection 24 on the pulley 23, the shaft 22 being driven 75 by the motor 30 as will be hereinafter described. At the same time the shaft 35 is rotated through the gearing 33 and 34 and the arm 40 is moved around over the contacts 38 by the arm 41 on shaft 35 engaging the pin 43 on the disk 39 which carries the arm 40. The arm 40 is therefore moved a distance commensurate with the length of the line of print. When it is desired to return the carriage, the motor 30 is set in operation in the appropriate direction and rotates the shaft 22 so as to wind up the flexible connection 24 upon the pulley 23. This rotation of shaft 22 effects rotation of shaft 35 in the opposite direction, thus causing 85 the arm 41 to move around in a counter-clockwise direction. But the disk 39 and arm 40 do not move with the arm 41 as the disk 39 is then held by the lever 45 which is moved into engagement with the teeth on 90 the disk 39 when the key 48 is depressed to start the motor 30. The rotary movement of shaft 35 and arm 31 continues until the arm engages the lever 49 and turns that lever against the tension of spring 50 so as to 95 break the electrical connection between the end of lever 49 and the pin 51 on arm 52. The breaking of the connection between arm 100 49 and pin 51 causes an amount of resistance to be cut into the motor circuit depending upon the position of the arm 40 and hence upon the extent of the advance movement of the carriage. The last portion of the return movement of the carriage is thus 105 effected with resistance in the motor circuit so that the torque of the motor is substantially reduced. When the return movement has been entirely completed, the operator 110 releases the key 48 and the latter is raised to its normal position and in the course of its movement operates the lever 45 to turn it out of engagement with the teeth of the ratchet on the disk 39. The disk being thus released is returned to its normal position by the 115 spring 44, which spring was placed under tension by the movement of shaft 35 which carried the arm 41 into engagement with lever 49.

The arm 29 of the controller is secured to a shaft 59 which extends through a bearing 120 in the casing of the return mechanism and to the inner end of this shaft is secured a block 60 of insulating material. This block has two contact arms 61 and 62 in the form of sheet metal strips secured thereto, the two 125

arms being spaced apart so that they are not electrically connected. Each of these two arms coöperates with contacts mounted upon a strip 63 of insulating material which is secured to the inner side of the end member of the casing of the return mechanism. The contact strip 61 has a spring 64 connected at one end thereto, its other end being connected to a stud 65 on the insulating wall 63. The contact arm 62 has a spring 66 connected at one end thereto, its other end being connected to a stud 67 on the wall 63. These two springs 64 and 66 exert a spring tension upon the arm of the controller including the arm 29, shaft 59, insulating block 60 and the contact strips 61 and 62. This tension is exerted against the flexible connection 24 and normally flexes it to the extent indicated in Fig. 1. When the flexible connection is flexed to this extent, the contact strips 61 and 62 are in the positions indicated in Fig. 8 and a contact button on the lower end of the strip 61 is then in engagement with a dead stud mounted upon the wall 63. Rocking of the controller arm in one direction or the other carries the button on the lower end of the strip 61 into engagement with one or the other of two contact studs 68 and 69 mounted upon the insulating wall 63. Also, when the controller arm is rocked thus, a contact on the lower end of the arm 62 is carried into engagement with one or the other of two contacts 70 and 71 mounted upon the insulating wall 63. The contact 70 is electrically connected to the contact 69 and the contact 71 is electrically connected to the contact 68, as will be seen by reference to Figs. 12, 13 and 14, so that these parts constitute a reversing switch for the circuit 40 of the motor 30.

The bracket 72 by which the contact 70 is mounted upon the insulating wall 63, carries two screws 73 and 74, the former of which is insulated from the bracket 72 by a bushing 75 (Fig. 10). These screws are normally in engagement with spring arms 76 and 77 which are secured to the under side of the base of the casing for the return mechanism, as shown in Fig. 8, and which project 50 from their points of support transversely of the casing. Each of these spring arms 76 and 77 carries a stud 78 (Figs. 5 and 8) and the two studs 78 project upwardly through openings in the base of the casing; the upper ends of these two studs 78 are adapted to be engaged by a projection 79 on the key lever 48 so that when the key lever is depressed the studs 78 are depressed, carrying with them the free ends of the spring arms 76 and 60 77. When the spring arms 76 and 77 are so depressed, contact studs 80 on the under sides thereof are carried into engagement with contact studs 81 and 82 mounted upon a bracket 83 secured to the base of the casing. The contact 81 is carried by a spring

arm 84 so that it is raised slightly above the contact 82, as a result of which the circuit is broken at the contact 82 rather than at the contact 81 when the spring arms 76 and 77 move upwardly out of engagement 70 with the underlying studs.

Figs. 12, 13 and 14 illustrate the electrical connections with the several switching devices shown in each of the three positions to which they are moved in operating the mechanism to perform its functions. Fig. 12 illustrates the positions which the parts occupy when the flexible connection 24 has been drawn abnormally taut by the letter spacing movements of the carriage and the motor is operating to feed out the flexible connection 24 to restore it to its normal condition. Fig. 13 illustrates the positions which the parts occupy when the flexible connection 24 has become abnormally slack 85 as a result of a partial return movement of the carriage effected manually. Fig. 14 illustrates the positions which the parts occupy when the key lever 48 has been depressed to cause the motor to return the carriage to its initial position. Referring first to Fig. 12, it will be seen that the positive supply wire 85 leads to the field coils of the motor 30 and then to the spring arm 76 which is adapted to be depressed by a depression of the key lever 48. When this spring arm 76 is not depressed, the contact thereon is in engagement with the screw 73 (Fig. 10) which is connected to the contacts 71 and 68. The negative supply wire 86 is 100 connected to the spring arm 77, which when it is not depressed by the key lever 48, is in engagement with the screw 74 which is connected to the contacts 70 and 69. The spring 66, which is connected to the contact arm 62 105 of the controller, is connected by a wire 87 to one side of the armature of the motor 30 and the other side of the armature is connected by wire 88 with the stud 89 on the base plate of the rheostat, to which the 110 spring 50 is connected. This spring electrically connects the wire 88 and stud 89 to the lever 49. The coacting lever 52 is connected by a wire 90 to the contact 81 underlying the spring arm 77. The contact 82 underlying 115 the spring arm 76 is connected, as shown, to the wire 87. The spring 64, which is connected to the spring arm 61 of the controller, is connected to the last one of the studs 38 of the rheostat and the first one of these 120 studs is connected by a wire 91 to the lever 49. The switch arm 40 of the rheostat is connected to the wire 90 by means of a spring 92 mounted on the base plate of the rheostat and bearing against the hub of the 125 disk 39.

Normally, the arm of the controller lies in the position in which it is illustrated in Fig. 8 and the circuits are open at all of the contacts 68, 69, 70 and 71. Also, the key lever 120

48 is in its elevated position so that the switch arms 76 and 77 are in engagement with the overlying contacts 73 and 74 and are disconnected from the underlying contacts 81 and 82. If the operator should then commence writing upon the typewriting machine, the carriage would be moved along by its spring to effect line spacing and as a result the flexible connection 24 would be drawn more taut. This would result in swinging the arm of the controller to the position in which it is illustrated in Fig. 12, in which the spring arm 61 is carried into engagement with the contact 68 and the spring arm 62 into engagement with the contact 70. Current then flows from the positive wire 85 through the field coils of the motor to the switch arm 76, contact 73, contact 68, arm 61 and spring 64, through the coils of the rheostat, wire 91, lever 49, spring 50, wire 88, through the armature of the motor 30, and then by wire 87, spring 66, spring arm 62, contact 70, contact 74 and spring arm 77 to the negative supply wire 86. The direction 25 of flow of the current through the armature under these conditions is indicated by the arrow on Fig. 12. This would result in operation of the motor in a direction appropriate for feeding out the flexible connection 24 so as to make it less taut, and as a result, allow the arm of the controller to move to the Fig. 8 position.

If the carriage of the typewriting mechanism were to be returned by hand more or less, the flexible connection 24 would become abnormally slack. This would result in turning of the arm of the controller to the position indicated in Fig. 13, in which position the spring arm 62 of the controller engages the contact 71 and the spring arm 61 engages the contact 69. The circuit established under these conditions may then be traced as follows: from the positive supply wire 85 through the field coils of the motor 30 to the spring arm 76, contact 73, contact 71, spring arm 62, spring 66, wire 87 to the armature of the motor, wire 88 to stud 89, spring 50, lever 49, wire 91, the coils of the rheostat, spring 64, spring arm 61, contact 69, contact 74, spring arm 77, and negative supply wire 86. The direction of flow of current through the armature of the motor 30 under these conditions is indicated by the arrow on Fig. 13, and it will be noted that this direction is the opposite of that indicated on Fig. 12. The closure of this circuit results in operation of the motor in reverse direction, causing winding up of the flexible connection 24 so as to take up the slack therein and restore the flexible connection together with the arm of the controller to the normal position.

The controller arm and the contacts associated therewith thus operate as a reversing switch such that when the arm is rocked to

one side, the motor circuit is closed in one direction, and when it is rocked to the opposite side, the motor circuit is closed in the other direction. Thus, movement of the controller arm to one side or the other of its normal position results in operation of the motor in the corresponding direction to either take up or feed out the flexible connection 24 which connects the return motor to the typewriter carriage. This mechanism therefore operates to always maintain the flexible connection 24 in a normal state of tautness, for if the connection becomes more slack, the motor starts in operation automatically in one direction appropriate for taking up that slack and if the flexible connection becomes too taut, the motor starts in operation automatically in the opposite direction so as to feed out the flexible connection and thus reduce the degree of tautness.

When the key lever 48 is depressed, the circuit is closed through the return motor in the direction to cause the motor to wind up the flexible connection 24 and thus return the carriage to its initial position. The connections whereby this is effected are independent of the reversing switch consisting of the controller arm and the contacts associated therewith, as the return of the carriage must be effected immediately upon depression of the key lever irrespective of the position in which the controller arm happens to be. On depression of the key lever 48, the pins 78 are depressed carrying with them the free ends of the spring arms 76 and 77, thus disconnecting the spring arms 76 and 77 from the screws 73 and 74, respectively, and carrying them into engagement with the contacts 82 and 81, respectively. This condition of the parts is illustrated in Fig. 14 and the circuit connections thus established may be traced as follows: from the positive supply wire 85, current flows through the field coils of the motor 30 to the switch arm 76, contact 82, wire 87, armature of the motor, wire 88, stud 89, spring 50, lever 49, pin 51, lever 52, wire 90, contact 81 and spring arm 77 to the negative supply wire 86. It will be noted that the direction of flow of the current through the armature of the motor is that indicated by the arrow on Fig. 14, and is the same as that indicated in Fig. 13 as being employed when the mechanism is operated to take up slack in the flexible connection 24. When the circuit indicated in Fig. 14 is closed, the motor starts operating and winds up the flexible connection 24 to return the carriage to the initial position. When this return movement of the carriage is started, none of the coils of the resistance 37 is in circuit and this condition prevails until the carriage nears the end of its return movement. Then the lever 49 is turned about its pivot to disconnect it from the pin 51, as has been here

tofore described. This opens the direct path for the current from lever 49 to lever 52 and wire 90 and instead the current flows from lever 49 by wire 91 through the coils 37 of the rheostat to switch arm 40 and then by spring 92 to the wire 90. Thus, a portion of the resistance 37 dependent upon the position of the switch arm 40 is connected in the circuit during the latter part of the return movement of the carriage to cut down the torque of the motor. As a result of this, the return movement of the carriage is initiated with the motor developing its full torque and the return movement is accomplished quickly with the development of substantial momentum. If the return movement be a long one during which the maximum momentum is developed, a large amount of resistance is cut into the motor circuit near the end of the return movement and the remainder of the return movement is effected by the momentum of the carriage. On the other hand, when a short return movement is to be effected, the motor is connected in circuit without any resistance and near the end of the short return movement, a relatively small amount of resistance is cut into the motor circuit to reduce the torque of the motor somewhat so that if the momentum of the carriage be insufficient to carry the carriage to the end of its return movement, the power of the motor will be available for that purpose.

When the circuit is closed by the automatic controller for taking up slack in the flexible connection, as shown in Fig. 13, or for feeding out the flexible connection, as shown in Fig. 12, the whole of the resistance 37 is included in the circuit, as under either of these conditions it is not desirable to have the motor develop its full torque. By reason of the inclusion of this resistance in the motor circuit when taking up slack and feeding out the flexible connection, the motor operates at greatly reduced torque, as is desirable under these conditions.

By reference to Figs. 12, 13 and 14, it will be seen that a condenser 93 is so connected in circuit as to bridge the gaps at which the circuits are broken and thus prevent objectionable sparking at the contacts.

By reference to Figs. 4 and 6, it will be seen that the worm wheel 34 is mutilated so that it is not provided with teeth over a portion of the peripheral surface of the gear. This is done to facilitate the substitution of a new flexible connection 24 in case of breakage. If such breakage were to occur, it would result in operation of the motor in a direction to wind up the flexible connection upon the pulley 23 and this would be accompanied by movement of the gear 34, sleeve 42 and arm 41 in a counter-clockwise direction, as seen in Fig. 4, until finally the arm 41 would engage the lever 49 and rock

that lever on its pivot and then move on to a position beyond that at which the arm 40 is normally arrested in the course of a return movement of the carriage. The mutilation of the gear 34 is such that when the arm 41 passes its normal position, the mutilated portion of the gear comes opposite the worm 33 and rotation of gear 34 is thus discontinued, even though the motor continues in operation. The operator may then stop the rotation of the motor by means of a suitable switch provided therefor. The parts of the broken band 24 are then removed and the shaft of the motor is rotated manually to carry the arm 41 around in a clockwise direction to the end of its range of movement, in which position the rheostat arm 40 bears upon the last one of the several contacts 38. In doing this, no difficulty will be experienced in causing the gears 33 and 34 to come into mesh as the spring 44 is then under tension in a direction to force the gear 34 into mesh with the worm 33. The operator may then attach one end of a new band to the pulley 23 and the opposite end to the carriage, the latter being at the extreme limit of its advance movement.

What I claim is:

1. The combination of a typewriter having a carriage, means for moving the carriage to effect letter spacing, a motor independent of said means and permanently connected to the carriage so that advance and return movements of the carriage are accompanied by forward-and reverse operation of the motor, and means for relieving the carriage of the drag of the motor when the carriage is moved to effect letter spacing; substantially as described.

2. The combination of a typewriter having a carriage, a spring for advancing the carriage to effect letter spacing, an electric motor adapted to operate in one direction to return the carriage, a connection from the motor to the carriage requiring operation of the motor in the other direction in correspondence with the advance movement of the carriage, and means for relieving the carriage of the drag of the motor when the carriage is moved by said spring; substantially as described.

3. The combination of a typewriter having a carriage, means for advancing the carriage to effect letter spacing, a motor adapted to operate in one direction to return the carriage, a connection from the motor to the carriage requiring operation of the motor in the other direction in correspondence with the advance movement of the carriage, and means for operating the motor automatically in correspondence with advance movements of the carriage; substantially as described.

4. The combination of a typewriter having a carriage, a motor adapted to operate in opposite directions, a connection from the

- motor to the carriage through which the motor effects the return of the carriage when the motor is operating in one direction, means independent of the motor for effecting advance movements of the carriage, and means for operating the motor in the opposite direction automatically to relieve said first named means from the drag of the motor during advance movements of the carriage; substantially as described. 10
5. The combination with a typewriter having a carriage, of a motor permanently connected to the carriage for effecting return movements of the carriage and adapted to operate in opposite directions as the carriage is moved in opposite directions, and means for effecting advance movements of the carriage unimpeded by the motor; substantially as described. 15
6. The combination with a typewriter having a carriage, of a motor permanently connected to the carriage for effecting return movements of the carriage, means for operating the motor to return the carriage, means independent of the motor for effecting advance movements of the carriage, and means for operating the motor automatically as the carriage is advanced to permit the carriage to be advanced unimpeded by the motor; substantially as described. 20
7. The combination with a typewriter having a carriage, of a motor permanently connected to the carriage for effecting return movements of the carriage, means for operating the motor to return the carriage, means independent of the motor for effecting advance movements of the carriage, and means for automatically operating the motor intermittently during advance movements of the carriage; substantially as described. 25
8. The combination with a typewriter having a carriage, of a motor for returning the carriage, a flexible connection from the carriage to the motor, and means for operating the motor to feed out the flexible connection during the advance movement of the carriage; substantially as described. 30
9. The combination with a typewriter having a carriage, of a motor for returning the carriage, a flexible connection from the carriage to the motor, and means for operating the motor automatically to feed out the flexible connection in accordance with letter spacing movements of the carriage; substantially as described. 35
10. The combination with a typewriter having a carriage, of an electric motor for returning the carriage, a flexible connection from the carriage to a shaft connected to the rotor of the motor, and means for operating the motor automatically during advance movements of the carriage to prevent rotation of said rotor by the carriage; substantially as described. 40
11. The combination with a typewriter having a carriage, of a motor for returning the carriage, a flexible connection from the carriage to the motor, and means for automatically operating the motor intermittently during advance movements of the carriage in writing a line of print to prevent operation of the motor by the carriage; substantially as described. 45
12. The combination with a typewriter having a carriage, of a motor for returning the carriage, a flexible connection from the carriage to the motor, a member contacting with the flexible connection, and means controlled by said member for causing operation of the motor to feed out the flexible connection as the advance movement of the carriage progresses; substantially as described. 50
13. The combination with a typewriter having a carriage, of a motor connected to the carriage, means for operating the motor to return the carriage, a member operated by advance movements of the carriage, and automatic means controlled by said member for causing operation of the motor in such direction that the advance movements of the carriage are unimpeded by the motor; substantially as described. 55
14. The combination with a typewriter having a carriage, of a motor for returning the carriage, a flexible connection from the carriage to the motor, a member contacting with the flexible connection, and automatic means controlled by said member for causing operation of the motor during advance movements of the carriage in such direction that in said movements the carriage is unimpeded by the motor; substantially as described. 60
15. The combination with a typewriter having a carriage, of an electric motor for returning the carriage, a flexible connection from the carriage to a shaft connected to the rotor of the motor, a member bearing on the flexible connection and automatic means operated by said member when the latter is actuated by an increase in the tautness of the flexible connection for causing operation of the motor to increase the flexure of the flexible connection; substantially as described. 65
16. The combination with a typewriter having a carriage, of a motor for returning the carriage, a connection from the carriage to the motor which is normally flexed a predetermined amount, and means operated by a decrease in the flexure of the connection occasioned by an advance movement of the carriage for operating the motor to restore the normal flexure of the connection; substantially as described. 70
17. The combination with a typewriter having a carriage, of a motor connected to the carriage, means operated by movement of the carriage in either direction for causing operation of the motor in a corresponding direction, and means for operating the mo- 75

- tor to return the carriage; substantially as described.
18. The combination with a typewriter having a carriage, of a motor for returning the carriage, a connection from the carriage to the motor which is normally flexed a predetermined amount, means operated by movement of the carriage in either direction changing the degree of flexure of said connection for causing operation of the motor in a corresponding direction to restore the connection to the predetermined condition of flexure, and means for operating the motor to return the carriage; substantially as described. 5
19. The combination with a typewriter having a carriage, of a motor for returning the carriage, a flexible connection from the carriage to the motor, an automatic controller coacting with the flexible connection and effecting operation of the motor in correspondence with letter spacing movements of the carriage, and means for operating the motor to return the carriage; substantially as described. 10
20. The combination with a typewriter having a carriage, of a motor connected to the carriage, an automatic controller for the motor operated in response to movement of the carriage in either direction and means for operating the motor to return the carriage; substantially as described. 15
21. The combination with a typewriter having a carriage, of a motor for returning the carriage, a flexible connection from the carriage to the motor, a member actuated in response to an increase or a decrease of the flexure of the flexible connection for causing operation of the motor in a direction to restore the normal flexure of the connection, and means for operating the motor to return the carriage; substantially as described. 20
22. The combination with a typewriter having a carriage, of an electric motor for returning the carriage, a flexible connection from the carriage to a shaft connected to the rotor of the motor, and a reversing switch in the motor circuit controlled by said connection; substantially as described. 25
23. The combination with a typewriter having a carriage, of an electric motor for returning the carriage, a flexible connection from the carriage to a shaft connected to the rotor of the motor, and a member coacting with the flexible connection and operated by an increase in the tautness thereof to close the circuit of the motor in a direction to cause the motor to increase the flexure of the flexible connection; substantially as described. 30
24. The combination with a typewriter having a carriage, of an electric motor for returning the carriage, a flexible connection from the carriage to a shaft connected to the rotor of the motor, a reversing switch 35
- in the motor circuit controlled by the flexible connection, and a key lever operable to close the motor circuit independently of the reversing switch; substantially as described.
25. The combination with a typewriter having a carriage, of a motor, a driven shaft, gearing between the shaft of the motor and the driven shaft, a pulley on the driven shaft, a flexible connection secured to the pulley and to the carriage of the typewriter, and automatic means operated by advance movements of the carriage in letter spacing for causing operation of the motor to feed out the flexible connection; substantially as described. 70
26. The combination with a typewriter having a carriage, of a motor, a driven shaft, gearing between the driven shaft and the shaft of the motor, a pulley on the driven shaft, a flexible connection secured to the pulley and to the carriage, a controller co-operating with the flexible connection and operated by an increase or a decrease in the flexure of said connection to cause operation of the motor in one direction or the other, and means for causing operation of the motor to return the carriage; substantially as described. 75
27. The combination with a typewriter having a carriage and a spring for moving the carriage to effect letter spacing, of a motor for returning the carriage after writing a line, a driven shaft, intermeshing gears on the driven shaft and the shaft of the motor, a pulley on the driven shaft, a flexible connection secured to the pulley and to the carriage, and means for relieving the spring from the drag of the motor when the carriage is moved by the spring; substantially as described. 80
28. The combination with a typewriter having a carriage, of an electric motor, a driven shaft, intermeshing gears on the driven shaft and the shaft of the motor, a pulley on the driven shaft, a flexible connection connecting the pulley and the carriage of the typewriter, and a rheostat connected in the circuit of the motor and having a movable member which is operated by the motor; substantially as described. 85
29. The combination with a typewriter having a carriage, of an electric motor, a flexible connection connected to the motor and to the carriage, a pivoted spring actuated arm bearing on the flexible connection, and contacts in the circuit of the motor engaged by the spring actuated arm when the latter is moved in either direction from its normal position for closing the motor circuit in one direction or the other depending upon the direction of movement of the spring actuated arm; substantially as described. 90
30. In a carriage return mechanism, a motor connected to the carriage, a rheostat 100

having a movable arm, a member driven by the motor and adapted to move the rheostat arm when the member is moved in one direction, and a switch operated by 5 said member when it is moved in the opposite direction, said switch controlling a short circuit around the portion of the rheostat which is connected in circuit by the movement of the movable arm of the rheostat; 10 substantially as described.

31. In a carriage return mechanism, a motor connected to the carriage, a rheostat having a movable arm, a member driven by the motor and adapted to move the 15 rheostat arm when the member is moved in one direction, and a switch operated by said member when it is moved in the opposite direction, said switch controlling a short circuit around the portion of the rheostat 20 which is connected in circuit by the movement of the movable arm of the rheostat, and means for effecting an adjustment of the said switch to determine the point at which the switch is opened by said member; 25 substantially as described.

32. In a carriage return mechanism, the combination of a motor adapted to be connected to the carriage to return the same, means for automatically reducing the torque 30 of the motor during the return movement of the carriage effected by the motor, and means for effecting an adjustment of the point in the return movement where the said reduction of the torque of the motor 35 occurs; substantially as described.

33. In a carriage return mechanism, an electric motor for effecting the return of the carriage, a rheostat having a movable member operated by the motor, means operated 40 automatically during the return movement of the carriage by the motor for connecting in the motor circuit a resistance whose value is dependent upon the extent of the advance movement of the carriage, and means for 45 effecting an adjustment of the point in the return movement of the carriage at which the said resistance is connected in the motor circuit; substantially as described.

34. In a carriage return mechanism, an 50 electric motor, a shaft driven thereby, a pulley on the shaft, a flexible connection extending from the pulley to the carriage of the typewriter, a rheostat controlling the operation of the motor, an operating member for the rheostat and intermeshing gears 55 connecting said operating member and said shaft, one of said gears being mutilated so that it is not provided with teeth over a predetermined portion thereof; substantially 60 as described.

35. The combination with a typewriter having a carriage, of a motor connected to the carriage for effecting the return thereof, and means for actuating the motor automatically when the carriage is advanced 65

during the writing of a line and when the carriage is moved forward and backward manually; substantially as described.

36. The combination with a typewriter having a carriage, of a motor, a flexible connection from the motor to the carriage through which the motor effects the return of the carriage, and means for actuating the motor automatically when the carriage is advanced during the writing of a line and 70 when the carriage is moved forward and backward manually; substantially as described.

37. The combination with a typewriter having a carriage, of an electric motor, a flexible connection from the shaft of the motor to the carriage, an automatic controller including a reversing switch in the circuit of the motor for operating the motor automatically when the carriage is moved 80 in either direction, a key and means operated by the key for closing the circuit of the motor independently of the reversing switch to cause the motor to wind up the flexible connection and thus effect the return of the carriage; substantially as described.

38. The combination with a typewriter having a carriage, of an electric motor for effecting the return of the carriage, means 90 including a reversing switch in the circuit of the motor for operating the motor automatically when the carriage is moved in one direction or the other, and key-controlled means for cutting out the reversing 100 switch and closing the circuit of the motor to cause the motor to effect the return of the carriage; substantially as described.

39. The combination with a typewriter having a carriage, of an electric motor connected to the carriage for effecting the return thereof, a resistance, means for closing circuit through the motor and said resistance automatically when the carriage is moved, and key-controlled means for closing the 105 circuit of the motor without the resistance therein to operate the motor to effect the return of the carriage; substantially as described.

40. The combination with a typewriter 115 having a carriage, of an electric motor connected to the carriage, a resistance, means for closing circuit through the motor and said resistance automatically when the carriage is moved in one direction when writing a line and when it is moved in either direction manually, and key-controlled means for closing the circuit of the motor without including the resistance therein to cause the 120 motor to effect the return of the carriage; substantially as described.

41. The combination with a typewriter having a carriage, of an electric motor, a flexible connection from the shaft of the motor to the carriage, a resistance, a tension 130

regulator operated by said connection and adapted to close the circuit automatically through the motor and said resistance, and key-controlled means for closing the circuit of the motor without including the resistance therein to cause the motor to effect the return of the carriage; substantially as described.

42. The combination with a typewriter having a carriage, of a motor connected to the carriage, key-controlled means for causing the motor to operate to effect the return of the carriage, and automatic means for causing operation of the motor with reduced torque when the carriage is moved in letter spacing and when it is moved manually; substantially as described.

43. The combination with a typewriter having a carriage, of an electric motor, a flexible connection from the motor to the carriage, key-controlled means for causing the motor to operate to return the carriage, and automatic means controlled by changes in the tension of the flexible connection for causing operation of the motor with reduced torque; substantially as described.

44. In a carriage return mechanism, a motor for effecting the return of the carriage, means operated automatically by the motor for reducing but not wholly discontinuing the effective power of the motor during the return movement of the carriage, and manually adjustable means for regulating as desired the point in the return movement where the said reducing means becomes operative; substantially as described.

45. In a carriage return mechanism, an electric motor for effecting the return of the carriage, means operated automatically by the motor for reducing but not wholly discontinuing the effective power of the motor during the return movement, said means including a circuit breaker for cutting resistance into the motor circuit, and manually adjustable means for regulating as desired the point during the return movement where the said reducing means becomes operative; substantially as described.

In testimony whereof I affix my signature. 50

NEAL LARKIN ANDERSON.
